UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,393,522.

Specification of Letters Patent. Patented Oct. 11, 1921.

Application filed October 25, 1918. Serial No. 259,629.

To all whom it may concern:

Be it known that I, CHARLES L. GOODRUM, a citizen of the United States, residing at New York, in the county of New York, 5 State of New York, have invented certain new and useful Improvements in Telephone-Exchange Systems, of which the following is a full, clear, concise, and exact description.

10 This invention relates to improvements in automatic telephone exchange systems and has particular reference to circuit arrangements for selector switches employed therein.

Heretofore, in two-wire automatic telephone exchange systems it has been customary to include one or more slow-to-release relays for controlling the primary and secondary stepping circuits of a selector switch. Such slow relays have their circuits interrupted by impulses sent over the telephone line but, due to their structure, the same are not sufficiently deenergized to permit their armatures to retract until a prolonged interruption occurs, whereupon certain changes are effected to complete the operation of the switch.

An object of this invention is to improve the construction and operation of selector switches by dispensing with the slow-to-release relays and providing contacts for the impulse receiving device of the selector switch, such as a line relay, one of said contacts being actuated in response to each operation of an impulse device at the calling subscriber's substation, and another contact being actuated in response to certain operations only of said impulse receiving device.

Another object is to release the selectively operable switch by a contact actuated, upon the permanent restoration of the impulse receiving device, to operate another contact which controls the release circuit of said switch, the second named contact being normally out of operative relation with said impulse receiving device and moved into operative relation therewith upon the initial energization of said device.

Briefly stated, the invention includes a slow moving or a sluggish device which is preferably associated with an impulse receiving device, such as a line relay, and provided with front and back contacts normally out of engagement with the armature of said relay but arranged so that when the same is initially energized the device will

be moved to a position where the armature, upon being vibrated in response to the line interruptions, will engage the back contact and close the primary stepping circuit of the selector switch. The device being sluggish in operation remains in its initially moved position during the vibrations of the armature. At the termination of the line interruption the usual escape magnet is energized to move the side switch of the selector into trunk hunting position, after which the magnet of the secondary stepping circuit will be energized to again step the selector in the usual manner to find an idle trunk. Upon the permanent restoration of the line relay by the replacing of the calling subscriber's receiver upon its switchhook during a period of time before the completion of the operation of the selector switch or at the termination of the conversation, the slow-acting contact-carrying device is returned to normal and closes a releasing circuit which aids in disconnecting the calling and called lines.

The inventive idea involved is capable of receiving a variety of expressions, one of which, for the purpose of illustrating the invention, is shown in the accompanying drawing; but it is to be expressly understood that said drawing is utilized only for the purpose of facilitating the description of the invention as a whole and not to define the limits thereof, reference being had to the appended claims for this purpose.

The drawing illustrates diagrammatically a telephone exchange system, only so much being shown of the circuit arrangements and apparatus as is necessary for a complete understanding of this invention.

The mechanical construction and operation of the selector switches and other apparatus used in establishing a connection between a calling and a called line, are features well known in the art, and therefore, in the following a detailed description will be given only of the operation of a selector switch used in the establishment of a connection.

The subscriber at substation 1, desiring a connection with substation 2, removes his receiver from its switchhook and causes the operation, in a well-known manner, of certain apparatus, such as a trunk finder or a line switch (not shown) to select an idle trunk leading to the selector switch 3.

When an idle trunk is found, a circuit is closed from grounded battery 4, left-hand winding of line relay 5, wiper 6 of the side switch associated with the switch 3, 5 substation apparatus 1, wiper 7 of said side switch and right-hand winding of line relay 5 to ground. The slow-acting or sluggish device 8 is pivotally mounted at 9 and carries contacts 10 and 11 arranged to be engaged 10 by the armature 12. The armature 12 of the line relay is normally positioned between and out of engagement with the contacts 10 and 11. Upon the energization 15 of line relay 5, armature 12 will pull up and engage contact 10 and rotate the device 8 about its pivot to position back contact 11 for engagement by said armature when the same is retracted. The calling subscriber now proceeds to set the selector switch 3 by operating his calling device 20 provided at the substation 1 for interrupting the circuit of the line relay. At each interruption of said circuit, armature 12 engages contact 11 and closes a circuit for 25 primary stepping magnet 13 extending from grounded battery 14 through the winding of said magnet, wiper 15 of the side switch in its first position, contact 11 and armature 12, to ground. The primary magnet 13 will step the selector switch in a manner well known in the art, until the first 30 series of impulses sent from the calling device is completed, whereupon armature 12 will be held attracted by line relay 5 for closing the operating circuit of slow-acting escape magnet 16, which circuit extends from grounded battery 14, winding of escape magnet 16, off-normal contact 17, which is closed upon the first step of the selector 35 switch, side-switch wiper 18 in its first position, resistance 19, contact 10 and armature 12, to ground. Escape magnet 16 is consequently energized, due to the prolonged engagement of armature 12 with front contact 10, and moves the side switch into second position, whereupon the circuit for the 40 primary magnet 13 is broken and another circuit for the secondary stepping magnet 20 closed which extends from grounded battery 14, winding of secondary magnet 20, armature and back contact thereof, wiper 21 of the side switch, to ground. The secondary magnet 20 is operated to control the 45 secondary stepping circuit of the selector switch 3. As long as the test brush 22 of the selector switch travels over terminals of busy trunks, no ground will be found for escape magnet 16, the circuit for which now extends from grounded contact 14, winding 50 of magnet 16, off-normal contact 17, wiper 18 in its second position and test brush 22. As soon as said brush reaches the terminal 55 of an idle trunk, that is, one to which ground is connected, the circuit for said escape magnet 16 is closed and the wipers 60

of the side switch are caused to move into position 3, in which position the calling line is extended through the wipers 6 and 7 of the side switch to another switching mechanism (not shown) provided between 70 the selector 3 and the called substation 2, and under the control of substation 1 the desired connection may be established in the well-known manner.

Upon the severing of the connection, a 75 ground is sent from the above-mentioned switching mechanism through brush 22, wiper 26, conductor 25 and winding of release magnet 24, to grounded battery 14, whereupon said release magnet will be energized in a well-known manner and return the selector switch 3 and associated side switch to normal position. After the side switch has been restored to normal and the receiver at substation 1 replaced, line relay 80 5 is deenergized, and armature 12 momentarily engages contact 11 and returns the device 8 to normal position, whereupon a ground is sent from spring contact 23 through conductors 28 and 29 and wiper 30 85 to the trunk finder or line switch, previously referred to but not shown, for causing the release thereof.

Should the subscriber at substation 1 abandon his call before the completion of 90 the operation of the primary and secondary stepping circuits, line relay 5 will be deenergized and the device 8 moved to its normal position. In this position the spring contact 23 will be closed, said contact having moved to open position upon the first 95 energization of line relay 5, and a circuit for release magnet 24 will be closed which extends from grounded battery 14, winding of release magnet 24, conductor 25, side-switch wiper 26 in either its first or second 100 positions, off-normal contact 27, conductor 28 and spring contact 23, to ground. The 105 energization of release magnet 24 will return the selector switch to normal position 110 in the well-known manner.

What is claimed is:

1. In a telephone exchange system including incoming and outgoing lines, a selector switch for interconnecting said lines, an impulse sender, a line relay operable in accordance with the impulses from said sender, primary and secondary magnets for moving said switch, an escape magnet, a release magnet, circuits for said magnets, a 115 contact for said line relay in the circuit of said primary magnet actuated in response to each impulse from said sender to move said selector switch, a second contact for said line relay in the circuit of said escape 120 magnet actuated upon the termination of a series of impulses from said sender to cause the operation of said secondary magnet, and a third contact for said line relay in the 125 circuit of said release magnet under the 130

control of said line relay but actuated only in response to certain operations thereof.

2. In a telephone exchange system including incoming and outgoing lines, a selector switch for extending an incoming line toward an outgoing line, a line relay associated with said selector switch, primary and secondary means for controlling the operation of said switch, a single movable means arranged in operative relation to said line relay for controlling the operation of said primary and secondary means, and means also controlled by said movable means for releasing said selector switch.
- 10 3. In a telephone exchange system including incoming and outgoing lines, a selector switch for extending an incoming line toward an outgoing line, a line relay associated with said selector switch, primary and secondary means for controlling the operation of said switch, and a contact-carrying device associated with the armature of said line relay for controlling said primary and secondary means, the contacts of said device being normally out of engagement with said armature and moved into coöperative relation therewith upon energization of said relay.
- 20 4. In a telephone exchange system including incoming and outgoing lines, a selector switch for extending an incoming line toward an outgoing line, a line relay associated with said selector switch, primary and secondary means for controlling the operation of said switch, and a rotatable device associated with the armature of said line relay and actuated in one direction thereby to coöperate therewith in controlling said primary and secondary means.
- 30 5. In a telephone exchange system including incoming and outgoing lines, a selector switch for extending an incoming line toward an outgoing line, a line relay associated with said selector switch, primary and secondary means for controlling the operation of said switch, a release circuit for said switch, and a rotatable device associated with the armature of said line relay and actuated in one direction thereby to coöperate therewith in controlling said primary and secondary means, said device being movable

in an opposite direction upon deenergization of said line relay to close said release circuit.

6. In a telephone exchange system including calling and called subscribers' lines, a selector switch for extending a calling subscriber's line toward a called subscriber's line, a line relay associated with said selector switch, means for operating said switch, a release circuit for the said switch, a movable contact-carrying device in operative relation to said line relay and actuated thereby to control the operating means of said switch, and means controlled by said device for closing said release circuit should a calling subscriber replace his receiver during the operation of said operating means.

- 15 7. In a telephone exchange system, an incoming line, a switch for extending said line, primary and secondary stepping magnets for operating said switch, an escape magnet for controlling the operation of said secondary stepping magnet, and a relay connected to said incoming line, said relay having contacts in the circuits of said primary and escape magnets, the contact in the circuit of said escape magnet being closed upon energization of said relay.

- 25 8. In a telephone exchange system, an incoming line, a switch for extending said line, a stepping magnet and an escape magnet for said switch, a relay connected directly to said incoming line, and circuits for said stepping and escape magnets passing through contacts of said relay, the contact in circuit with said escape magnet being closed upon energization of said relay.

- 35 9. In a telephone exchange system, an incoming line, a switch for extending said line, a stepping magnet, an escape magnet and a release magnet for said switch, a relay operable over said incoming line, and circuits for said magnets passing through contacts of said relay, the contact through which the circuit of said release magnet passes remaining open during the operation of said switch.

In witness whereof I hereunto subscribe my name this 21st day of October, A. D. 100 1918.

CHARLES L. GOODRUM.
